UNITED STATES PATENT OFFICE.

GEORGE A. BUBAR, OF MINNEAPOLIS, MINNESOTA ASSIGNOR TO BELL LUMBER COMPANY, OF MINNEAPOLIS, MINNESOTA, A CORPORATION OF MINNESOTA.

METHOD AND MEANS FOR TREATING WOOD POLES.

Application filed April 30, 1926. Serial No. 105,728.

This invention relates to an improved method and means for treating wooden poles and timbers preparatory to impregnating them with a preserving fluid to prevent deterioration of the wood fibers; and more particularly relates to such a method which consists in hammering, prior to impregnation, substantially the entire circumferential surface of that portion of the pole or timber to be impregnated, thereby disrupting or separating the wood fibers sufficiently to allow a preserving fluid to penetrate the surface of the pole, without cutting or severing the fibers thereof during the operation, a common practice with machines in general use; such machines usually being provided with means for piercing the surface of the pole, and severing of the wood fibers with a resulting objectionable weakening of the pole.

It is well known that wooden telegraph or telephone poles, having a portion thereof sunk or set into the ground, deteriorate or decay at the ground line, in a comparatively short time, unless such portion or area of the pole has been impregnated or treated with a suitable preserving fluid such, for instance, as creosote. Before the preserving fluid can penetrate into the surface of the wood to a depth sufficient to prevent deterioration thereof, the surface is usually punctured to allow the preserving fluid to readily penetrate between the fibers.

An object of this invention is to provide an apparatus for thus treating and conditioning the surface of a pole or timber to receive a suitable fluid preservative and comprising a fluid-operated hammering device adapted to engage the surface of the pole and to hammer and pound it in rapid succession, whereby the wood fibers will become disrupted or separated sufficiently without being severed to allow the preserving fluid to readily penetrate the surface of the pole.

A further object of the invention is to provide such an apparatus of comparatively small size and light weight, comprising a supporting carriage having anti-friction carrying rollers adapted to engage and roll upon the surface of the pole or timber to carry the weight of the carriage and associated parts, and to provide a guide therefor; the fluid-operated hammering or mauling device being mounted on the carriage and having a flexible connection with a source of fluid supply such, for instance, as

a compressor, whereby the apparatus may readily and conveniently be moved over the surface of the pole to condition it prior to being impregnated with a preserving fluid.

The particular object of the invention, is to provide an improved method and means for treating, by hammering and pounding, the surface of a pole or timber prior to being impregnated with a preserving fluid, whereby the fluid may penetrate into the wood sufficiently deep to render it substantially waterproof.

Other objects of the invention will appear from the following description, and the accompanying drawings and will be pointed out in the annexed claims.

In the drawings there has been disclosed a structure designed to carry out various objects of the invention, but it is to be understood that the invention is not confined to the exact features shown, as various changes may be made within the scope of the claims which follow.

In the accompanying drawings forming a part of this specification,

Figure 1 is a vertical sectional view of the apparatus showing it positioned upon a portion of a pole or timber, and also showing the general construction thereof;

Figure 2 is a plan view of Figure 1;

Figure 3 is a cross-sectional view on the line 3—3 of Figure 1, showing the means provided for controlling the operation of the fluid-operated hammering device;

Figure 4 is a diagrammatic view illustrating the apparatus positioned upon the surface of a pole, the shaded portion indicating the area of the pole which has been subjected to the hammering or mauling treatment.

The novel device featured in this invention preferably comprises a carriage 5 having carrying rollers 6 provided at each end thereof adapted to roll upon the surface of the pole or timber, as shown in Figures 1 and 4, to carry the weight of the device. Suitable handles 7 and 8 are provided at each end of the base plate 5 whereby the device may conveniently be manually operated back and forth upon the surface of the pole as shown in Figure 4.

The means provided for hammering, mauling or pounding the surface of the pole preferably consists of a disc-like or circular hammer head 9, demountably secured to

the threaded end portion 11 of a connecting rod 12 having its other end secured to a piston 13, reciprocally mounted in a bore 14 provided in a removable cylinder 15, as shown in Figure 1. The lower portion of the cylinder 15 is mounted in a bore 16 provided in the raised portion 17 of the base plate 5. The enlarged threaded portion 18 of the cylinder is secured to a collar 19 mounted upon the raised portion 17 of the carriage 5, and secured thereto by means of bolts or cap screws 21 as shown. Thus the cylinder will be securely held in the raised portion 17 of the plate 5. An enlarged bore 22 is provided in the lower portion of the carriage 5 to receive the hammer head 9, which also cooperates with the piston 15 to provide a support therefor.

The device herein shown is of the fluid pressure operated type, and comprises a valve mechanism mounted at the upper end of the cylinder within a housing 23, preferably secured to the enlarged portion 18 of the cylinder by suitable threads as shown. This valve mechanism is of ordinary well-known construction such as is commonly employed in air hammers and similar devices, and therefore need not be described in detail. Briefly, it comprises a valve casing 24 having a valve 25 movably mounted therein to control the flow of fluid pressure from the intake port 26 to the bore 14 of the cylinder, by means of the ports 27 and 28. The port 28 communicates with the annular space 29 around the valve casing 24 and with the exhaust port 31 as shown.

The intake port 26 leads from the upper portion of the housing 23 downwardly through the collar 19, raised portion 17 of the carriage 5 and through the latter, as indicated by the dotted lines in Figures 1 and 3, and terminates in a bore 32 provided in the handle 8 as shown in Figure 3. A small plunger 33 is reciprocally mounted in the bore 32 adapted to open and close the intake port 26 to the bore 32 as shown. The bore 32 communicates with a flexible fluid supply pipe 34 through a coupling 35 connected with the handle 8, as shown particularly in Figures 1 and 2. A small throttle lever 36 is pivotally mounted in the handle 8 and has an extension 37 adapted to terminally engage the plunger 33 which normally is held in closed position by means of a spring 38, mounted in a plug 39 as shown in Figure 3. Thus when the throttle lever 36 is depressed, the plunger 33 will be longitudinally moved in the bore 32 to uncover the intake port 26, thereby establishing communication between the intake port and the fluid supply pipe 34 with the resultant operation of the valve mechanism at the upper end of the cylinder and therefore the piston 13 within the bore 14.

In the operation of this novel device, the

pole or timber is preferably mounted upon a suitable supporting means such as the roller block 41, shown in Figure 4, whereby the pole may be conveniently rotated while the periphery thereof is being hammered or maulled with this novel device. The device here shown is of the portable type, and its weight is such that it may be conveniently handled by an operator by simply gripping the handles 7 and 8 and moving the device, as a whole, back and forth upon the periphery of the pole while the hammer head is being actuated to forcibly engage the surface of the pole and hammer it by rapid successive blows, thereby mauling and pounding the surface thereof as indicated by the shaded portion shown in Figure 4. Such mauling and pounding of the periphery of the pole will soften the wood fibers and cause these to become disrupted or separated sufficiently to allow a preserving fluid to readily penetrate into the surface of the pole, a distance sufficient to render the impregnated portion of the pole substantially moisture proof. By thus hammering the surface of the pole the wood fibers will not be cut or severed but will be softened and separated sufficiently to allow the pole to absorb a preserving fluid without weakening it, as frequently happens in devices which usually have means for piercing the surface of the pole with the resultant transverse cutting and severing of the wood fibers.

I claim as my invention:

1. A device of the class described comprising a carriage adapted to be moved back and forth over a circumferential surface of a pole, and means mounted in said carriage for mauling or pounding the surface of the pole to soften and separate the fibers thereof, and thereby adapt the surface of the pole to be thoroughly impregnated with a preserving fluid.

2. A device of the class described comprising a carriage having hand-grips for convenience in moving it back and forth over the peripheral surface of a pole, and a hammering or mauling means mounted in said carriage and adapted to pound and disrupt the surface fibers of the wood.

3. A device of the class described comprising a reciprocating mauling hammer having a blunt face for pounding and separating the surface fibers of a pole, and a suitable carriage wherein said mauling hammer is mounted.

4. A device of the class described comprising a carriage adapted to rest upon and be moved back and forth over the peripheral surface of a pole, and a fluid pressure actuated mauling hammer mounted in said carriage for pounding the surface of the pole and separating and softening the fibers thereof.

5. A device of the class described com-

prising a mauling hammer having a face to engage the surface of a pole and disrupt and separate the fibers thereof, and a support or carrier wherein said mauling hammer is mounted.

6. A device of the class described comprising a carriage adapted to be moved back and forth over the surface of a pole to be treated, a fluid pressure actuated mauling hammer mounted in said carriage and having a reciprocating movement for pounding and softening the surface fibers of the pole, a cylinder whereto the fluid pressure is delivered, and a valve for regulating the flow of fluid pressure to said cylinder.

7. A device of the class described comprising a suitable base having means for supporting it for movement back and forth over the surface of a pole, a reciprocating mauling hammer mounted on said base and comprising a plunger having a flat faced mauling head, a cylinder wherein said plunger is movable, and valve controlled means for delivering fluid pressure to said cylinder.

25 8. A device of the class described comprising a support for the end of the pole to be treated and whereon the pole is adapted to be rotated, a carriage movable back and forth over the surface of the pole, a fluid pressure actuated mauling hammer mounted in said carriage and having a face for pounding and softening the surface of the pole to receive a preserving fluid and manually controlled means for regulating the operation of said hammer.

9. A device of the class described, comprising in combination, a supporting carriage adapted to bear on the surface of a wooden pole or timber, a bore in said supporting carriage, a fluid-operated piston reciprocally mounted in said bore, means for controlling the operation of said piston, and a disc-like head connected with said piston and operable thereby to hammer the surface of said pole or timber, whereby the wood fibers thereof will separate to allow a pre-

serving fluid to penetrate the surface of said pole or timber.

10. A device of the class described, comprising in combination, a supporting member adapted to be moved over the surface of a log or pole, a cylinder mounted in said member, a fluid-operated piston reciprocally mounted in said cylinder, and a disc-like head connected with said piston and operable thereby to forcibly strike the surface of said log in rapid succession when said piston is operated, thereby separating or disrupting the wood fibers to allow a liquid preservative to penetrate the surface.

11. A device of the class described, comprising a carriage having carrying rollers thereon adapted to engage the periphery of a wooden pole or timber whereby it may be moved over the surface thereof, a cylinder mounted in said carriage and having a connection with a source of fluid supply under pressure, a piston reciprocally mounted in said cylinder, a hammer head connected with said piston, and operable therewith, and a valve mechanism for controlling the operation of said piston whereby, when said carriage is moved over the surface of a pole, said hammer head may be operated to hammer the surface of said pole in rapid succession, thereby separating the fibers of the pole to allow a liquid preservative to penetrate the surface thereof.

12. A method of treating wooden poles and timbers, to adapt them for absorbing a preserving fluid which consists in hammering or mauling a surface thereof to disrupt and soften the wood fibers.

13. A method of treating wooden poles to adapt them for absorbing a preserving fluid which consists in mauling or hammering a peripheral circumferential surface thereof to soften or separate the wood fibers, during rotation of the pole.

In witness whereof, I have hereunto set my hand this 27th day of April, 1926.

GEORGE A. BUBAR.
